ABSTRACT

A book supporting rack, which is comparable, in a manner of speaking, to a book inclining lectern but which, instead of being atop a pedestal, is designed and adapted to be positioned for use atop a table, a desk or an equivalent relatively stationary support surface. The rack is light in weight and may, if desired, be made of colorful, moldable, plastic material and is characterized by top, side and back walls. The top wall comprises a panel which has a smooth planar surface of an area capable of receiving and supporting an open book in an inclined position and wherein said panel is elevated by an inclining base. The base comprises an upstanding back wall and complemental side walls, and said back and side walls having upper edges united with corresponding marginal edge portions of the top wall or panel. The back and side walls have longitudinal bottom edges which are disposed in a common plane to rest firmly and evenly on a table or the like. The top wall panel has a lower longitudinal edge portion provided with an upstanding rib which constitutes a book positioning and retaining ledge.

BOOK SUPPORTING AND READING RACK

The present invention relates to a portable book supporting and reading rack which is simple, practical, attractive in appearance, which functions to supportively retain an open book in an inclined easy-to-read position and which presents the book at a satisfactory inclination such that the pages thereof are positioned at approximate right angles to the line of vision.

Persons conversant with the field of endeavor under consideration herein are aware that portable stands and desks of many and varying types have been devised by others working in this field and with a view toward reliably and effectually elevating and inclining books of varying sizes and weight. It follows that an object of the present invention, generally stated, is to advance the art of portable book supporting and reading racks and, in so doing, to provide an adaptation which is structurally and functionally novel, is capable of being satisfactorily manufactured from varying and economical materials, which can be properly endorsed by manufacturers and retailers, and which well serves the purposes for which it has been perfected and satisfactorily used.

For background information and because it has a general bearing on the subject matter of the invention under advisement, the reader may take into account, if so desired, the pedestal type copy holder and book support shown in U.S. Pat. No. 651,058, granted to George H. Rogers and for the reason that it shows a ledge-equipped inclined book propping and presenting panel but is otherwise of no moment. Also, and because it shows a one-piece easel type stand or rack made from moldable plastic material attention, if so desired, may be accorded the portable rack-type easel in U.S. Pat. No. 3,599,925, granted to Dorothea L. Dubler. Other but now outmoded book holders and racks could be, but need not be, herein referred to for state-of-the-art purposes.

Briefly the herein disclosed concept has to do, broadly stated, with an innovation which is characterized as a portable book supporting and reading rack and which is expressly designed and acceptably adapted to be reliably positioned for convenient and practical use atop a table, desk or an equivalent relatively stationary support surface. As will be evident by glancing at the views of the drawing, the adopted construction lends itself to acceptable and approved use in that the component parts are united to provide a well balanced and symmetrical end product which has been found to be pleasing in appearance and such in construction that it may be made of one-piece moldable plastic material or made from suitable wooden components, also fiber glass. To the ends desired, the finished product comprises a top wall or panel having an upper planar surface which is of an area capable of receiving an open book in a supportively readable inclined position. The panel is supported by a depending elevating and inclining base, the panel being fixedly mounted atop the component parts of the base. The component parts comprise an upstanding back wall and complementary side walls having coordinating ends joined together and also having upper edges united with and corresponding to marginal edge portions of the top wall or panel. The back and side walls have longitudinal bottom edges disposed in a common plane. The panel has a lower longitudinal edge portion provided with a book positioning and retaining ledge. The underneath sur-

face of the panel is provided with interconnected ribs providing honeycomb type panel reinforcing means.

In carrying out the principles of the invention and stated somewhat more explicitly the entire lower edge 5 of the top wall or panel is increased in cross-sectional thickness, is wedge-shaped in cross section and provides a flat bottom rigidifying rib. The bottom of this rib is in a plane common with the longitudinal bottom edges of the side walls and back wall, the side walls 10 being substantially triangulate in side elevation and sloping outwardly and downwardly or, conversely, upwardly and inwardly to provide the desired appearance and shape and to facilitate molding and to permit, if so desired, stacking of a plurality of the book racks for 15 packaging, transmitting and for other merchandising purposes.

These together with other objects and advantages which will become subsequently apparent reside in the details of construction and operation as more fully 20 hereinafter described and claimed, reference being had to the accompanying drawings forming a part hereof, wherein like numerals refer to like parts throughout.

FIG. 1 is a view in perspective of a book supporting and reading rack constructed in accordance with the 25 principles of the present invention.

FIG. 2 is an enlarged view taken approximately on the plane of the section line 2—2 of FIG. 1, looking in the direction of the indicating arrows.

FIG. 3 is a bottom plan view the purpose of which is to show the main rigidifying rib across the leading or forward edge and, more particularly, to show the auxiliary interconnected ribs defining the aforementioned honeycomb-type panel reinforcing and stabilizing means.

FIG. 4 is an end view on a suitably small scale looking at FIG. 2 in a direction from right to left.

By way of introduction to the description of the details, it is reiterated that the construction of the overall book supporting and reading rack is such that it may be of one piece form and under which circumstances it would preferably be made from high-impact colorful, commercial plastics or fiber glass. On the other hand and although not shown in detail, the component parts could be made of wood put together in such a manner as to achieve an overall one-piece concept. The reading rack, construed as a structural entity, is denoted by the numeral 6 and comprises a substantially rectangular top wall or, more specifically, a panel 8 which can be said to be rectangular in plan and which has a smooth planar top surface 10. The lower or leading marginal edge of this panel is denoted at 12 and is provided with an upstanding rigidly attached elongated rib 14 which may be of a length commensurate in length with the edge or shorter if necessary. In any event this rib provides, in conjunction with the surface 10, a ledge and supporting rack for a book (not shown). The underneath side of the top wall or panel is denoted by the numeral 16 in FIG. 2 and as shown here and also in FIG. 3 the overall surface is provided with reinforcing means which is referred to broadly as honeycomb reinforcing means 18 and is made up of interconnected companion longitudinal and transverse ribs 20 and 22. These ribs may be sufficiently close together that the pocket-like recesses are approximately one inch square. The upper marginal edge of the panel or top wall is denoted at 24. With reference in particular to FIGS. 2 and 3, the leading or lower edge 12 is increased in cross section as at

26 to provide a substantially wedge-shaped rigidifying and stabilizing member 28 which may be also considered as a rib and which is complementary to the aforementioned auxiliary ribs 20 and 22. The flat bottom surface of the rib 28 is flush with the lower edges 30 and 32 of the several walls which go to make up the supporting and elevating base 34. The back wall is denoted at 36 and the upper median portion is provided with an ovate or an equivalent opening 38 which serves to accommodate two or more fingers and provides a satisfactory finger-grip for lifting and other handling requirements. The side walls which coact with the back wall are denoted at 40 and can be described as being substantially triangulate in side elevation. These several base-forming walls coordinate in providing not only a self-standing base suitable for use on a table, desk or the like but also means which serves to give the desired 24 degree slope or incline to the top wall panel 8.

It will be understood that materials, shape and size are not critical but may be touched upon in a general manner for the reason that experience has shown that the base 34 should be the same length as the top panel 8. The top panel may be some 12 inches more or less in length whereas the lower edge of the back wall 32 may be approximately 13½ inches. The height of the outwardly and downwardly sloping (conversely inwardly and upwardly inclining) walls can be some 3⅓th inches if so desired. The length of the side walls and also the top wall may be and generally is some 9 inches. The reading rack holds an open book tilted at an angle of 24°. To a person sitting at a table or desk this unique reading rack presents the pages of the book at approximately a right angle to his line of sight. This is an ideal position for good vision. As mentioned and broadly reiterated, the rack is such in construction that several racks can be nested together for economy in packaging and for warehousing and shipping. It will also be clear that the reading rack could be made in various other sizes all using approximately the same design and the 24 degree angle of pitch. Then too, it will be evident that when the views are considered singly and collectively a clear and comprehensive understanding of the invention will be had, for which reason a more extended description is deemed to be unnecessary.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

I claim:

1. A portable book supporting and reading rack expressly designed and adapted to be positioned for convenient use atop a table, desk or an equivalent relatively stationary support surface comprising, a panel having a top planar surface of an area capable of receiving an open book in a supportively readable position, and a depending elevating and inclining base atop which said panel is fixedly mounted, said base embodying an upstanding back wall and complementary side walls having coordinating vertical ends

joined together, and also having upper horizontal edges united with corresponding marginal edge portions of said panel, said back and side walls having longitudinal bottom edges disposed in a common plane, said panel 5 having a lower longitudinal edge portion provided with a book positioning and retaining ledge, the underneath surface of said panel being provided with and stabilized by integral interconnected ribs providing honeycomb-type panel reinforcing means, the underneath side of 10 the entire leading lower edge of said panel being increased in cross-sectional thickness, wedge-shaped in cross-section and providing a flat-bottomed rigidifying rib, the flat-bottomed surface being in a plane common with the coordinating longitudinal bottom edges of said 15 side walls.

2. The book supporting and reading rack defined in and according to claim 1, and wherein said side walls are substantially triangulate in side elevation, said back wall being approximately rectangular in rear elevation.

20 3. The book supporting and reading rack defined in and according to claim 1, and wherein said side walls are substantially triangulate in side elevation, said back wall being approximately rectangular in rear elevation, 25 said back wall having an upper median portion provided with an opening constituting a conveniently usable finger-grip and which assists one in picking up and otherwise handling the overall rack.

4. The book supporting and reading rack defined in and according to claim 2, and wherein said back wall 30 and also said side walls incline upwardly and inwardly toward said panel and said panel is inclined upwardly at an angle of approximately 24 degrees, whereby to prop the book up in a manner comparable with a book which is being read from a conveniently sloped easy-to-cope-with lectern.

5. A portable book supporting and reading rack expressly designed and adapted to be positioned for convenient use atop a table, desk or an equivalent relatively stationary support surface comprising, a panel 40 having a top planar surface of an area capable of receiving an open book in a supportively readable position, and a depending elevating and inclining base atop which said panel is fixedly mounted, said base embodying a substantially rectangular upstanding back wall of a length corresponding to the upper edge of said panel, 45 said back wall sloping outwardly and downwardly and being provided with a finger accommodating opening, said base also embodying complementary side walls having upper edges joined to corresponding marginal edges of the top wall, said side walls being approximately triangulate in side elevation, the lower edges of all of said walls, side and back, being in a common plane, the underneath surface of said panel being provided with and stabilized by integral interconnected ribs providing honeycomb-type panel reinforcing means, the underneath side of the entire leading lower edge of said panel being increased in cross-sectional thickness, wedge-shaped in cross section and providing 50 a flat-bottomed rigidifying rib, the flat-bottomed surface being in a plane common with the coordinating longitudinal bottom edges of said side walls.
